United States Patent Office

Des. 229,630

Patented Dec. 18, 1973

229,630

FINGER-OPERATED INDICATING DEVICE

Sherwin L. Wafford, 590 E. Buchtel Ave.,
Akron, Ohio 44304

Filed Aug. 25, 1972, Ser. No. 283,741

Term of patent 14 years

Int. Cl. D10—04

U.S. Cl. D52—6 A

FIG. 1

FIG. 2

FIG. 3

FIG. 4

FIG. 5

FIG. 1 is a rear perspective view of a finger rule showing my new design.

FIG. 2 is a top plan view thereof.

FIG. 3 is a left side elevational view thereof.

FIG. 4 is a rear elevational view thereof.

FIG. 5 is a front elevational view thereof.

I claim:

The ornamental design for a finger-operated indicating device, as shown.
